[57] CLAIM

The ornamental design for a food dish, as shown and described.

DESCRIPTION

FIG. 1 is a top, front perspective view of a food dish, showing my new design;

FIG. 2 is a front elevational view thereof, the rear elevational view being a mirror image thereof;

FIG. 3 is a left side elevational view thereof, the right side elevational view being a mirror image thereof; and

FIG. 4 is a top plan view thereof.

The bottom plan view of the food dish, not shown, is plane and unornamented.

FIG. 1

FIG. 2

FIG. 3

FIG. 4
